UNITED STATES PATENT OFFICE.

WILLIAM R. SCHWAB, OF KANSAS CITY, MISSOURI, ASSIGNEE TO THE CAMERAGRAPH COMPANY, OF KANSAS CITY, MISSOURI, A CORPORATION OF ARIZONA.

PHOTOGRAPHIC APPARATUS.

1,266,060.

Specification of Letters Patent. Patented May 14, 1913.

Application filed January 15, 1913. Serial No. 742,289.

To all whom it may concern:

Be it known that I, WILLIAM R. SCHWAB, a citizen of the United States, residing at Kansas City, in the county of Jackson and 5 State of Missouri, have invented new and useful Improvements in Photographic Apparatus, of which the following is a specification.

This invention relates to improvements in 10 the art of photography, and the object thereof is to provide means whereby photographic reproductions of suitable size may be made with accuracy and facility. According to the present invention, means is 15 provided which indicates the dimensions of the object and serves to center or position the same properly on its support, such means also indicating the necessary adjustments of the object support and the camera lens in 20 order to obtain reproductions of the desired size, and indicating the amounts of sensitized material required for the reproductions of objects of different sizes.

To these and other ends, the invention 25 consists in certain improvements, and combinations and arrangements of parts, all as will be hereinafter more fully described, the novel features being pointed out particularly in the claims at the end of the specification.

In the accompanying drawings:—

Figure 1 represents an object support in the form of a chart and forming a part of the present invention;

35 Fig. 2 represents a card which, when used in connection with the object support or chart, provides the necessary data for the photographer;

40 Fig. 3 is a diagram showing the manner in which the data obtained by the aid of the chart and card is utilized.

Similar parts are designated by the same reference characters in the several views.

The object support 1 consists preferably 45 of a board or other suitable flat surface, and the object to be reproduced, such for example as a picture or writing or printed matter contained on a sheet, is applied to the face of the support and may be held in position thereon by any suitable means. The present invention is applicable especially to photographic apparatus of the type disclosed fully in Letters Patent, No. 929,757 granted August 3, 1909, to C. J. Ellis, and 50 the object support is adapted to be mounted

upon the copyholder shown therein. The face of the object support embodies a chart which performs the dual function of centering or positioning the object properly thereon and indicating the dimensions of the object. This chart is composed in the present instance of a series of rectangular diagrams 60 2 which increase progressively in size in a direction from the center toward the margin of the support, the diagrams being concentric. Index characters 3 serve to distinguish the different rectangular diagrams. Fig. 1 shows the chart as viewed in front elevation, this being the position that it occupies while in use. Series of lines 4 radiate from the center toward the two lateral sides of the chart, these lines being spaced vertically at predetermined intervals and such lines serve to indicate the lengths of sensitized material which it is necessary to 65 use in making reproductions of different sizes. These lines are preferably provided with index numbers, as shown, which designate directly and by inches the lengths of sensitized material which it is necessary to 70 use in making reproductions of objects which cover or fill but partially one of the rectangular diagrams on the chart. These radiating lines perform this function irrespective of the size of the object, as the vertical distance between such lines varies in accordance with the variations in the size of the object.

A chart of this character is adapted for 75 use in connection, for example, with the ordinary camera or photographic apparatus which produces a single image or exposes but one side of a sensitized medium. The chart shown, however, is also adapted for use in connection with a photographic apparatus of the type shown and described in 80 my prior Patent, No. 1,003,300 granted September 12, 1911, which is capable of exposing both sides of a sensitized medium or two sensitized mediums placed back to back, 85 in which case one sensitized surface receives the image from the object on the right-hand side of the object support while the other sensitized surface receives an image from the object on the left-hand side of the 90 object support. For this purpose, the chart is divided centrally to form right and left-hand sections, as shown.

The card 5 which is to be used in connection with the chart is shown in Fig. 2 and 95 110

it contains tabulated data which can be obtained immediately from the chart after the object is positioned thereon. For example, this card is provided with a column 6 containing numerals or index characters which correspond to those on the chart which designate the graduated rectangular diagrams. The card is also provided with a column 7 containing numerals which designate the horizontal dimensions of the graduated half squares, that is to say, the horizontal dimensions of those sections of the rectangular diagrams at the right or the left side of the central division between the chart sections. The column 8 contains data as to the horizontal dimensions of the complete squares or rectangular diagrams, while the column 9 contains data as to the vertical dimensions of the various squares or rectangular diagrams.

The chart and card are to be used in connection with photographic apparatus wherein in the camera lens front 10 which is movable axially of the lens 11 for focusing purposes is provided with a scale 12 which indicates the various focusing positions thereof, and the copyholder or object support is also movable in a direction in alignment with the camera lens and is provided with a scale 13 which designates the different positions thereof. Preferably, the photographic apparatus should also embody means for feeding paper or other sensitized material to the focal plane in measured lengths. It is preferable to employ a feeding and measuring device such as that shown and described in my prior patent, No. 1,053,068, granted February 11, 1913, as a device of that character not only facilitates the feeding of the sensitized material, but it also measures the material at each operation. Briefly described, the feeding and measuring device embodies a crank 14 which is operatively connected to rollers which advance the paper or sensitized material from a roll to the focal plane, and a handle 15 serves to adjust the limit of operation of the crank to different degrees as may be required. This feeding and measuring device is provided with a scale 16 which contains designating numerals or characters which indicate the different positions in which the handle 15 is to be set. The card shown in Fig. 2 contains data which enables the operator to quickly set the object support, camera lens, and the feeding and measuring device according to the different reproductions to be made, the column 17 on the card containing data which indicates the adjustment for the camera lens, and the column 18 containing data indicating the different positions in which the object support is to be set. The setting of the measuring device depends on the vertical height of the image cast upon the sensitized material, and this data is obtained upon

reference to the lines 4 on the chart which indicate the length of material required when the object covers one of the squares throughout its vertical height, as well as any fraction thereof. The card has the data so arranged thereon that all information concerning each square or rectangular diagram on the chart is contained on the same horizontal line with the index numeral or character which corresponds to the respective square, and all of the data above referred to can be obtained immediately upon reference to the column 6 of the card after the object has been placed in the proper square on the chart.

For example, the object *a, b* (Fig. 3) to be photographed is placed centrally on the copyholder or chart so that the object fits over or within one of the numbered diagrams, notation being made of the designating or index numeral of that diagram which, for example, may be No. 15, corresponding to an object 19 inches wide or horizontal dimension and 13 $\frac{1}{4}$ inches high, as will appear from the focusing card, Fig. 2. By reference to the focusing card it will also appear that the lens is to be set with reference to its scale 12 so as to be opposite to the character 10 $\frac{1}{2}$. The column 18 of the focusing card indicates that when the object is in the form of a sheet applied directly to the copyholder chart 1, the copyholder is to be set at 8 $\frac{1}{8}$ on its scale. When a bookholder is employed, the column to the right of the column 18 of the focusing card indicates that the copyholder is to be set at 13 $\frac{7}{8}$ on its scale. In each instance where the object fills the space within any diagram, the reproduced copy will be of the full size afforded by the camera.

The radiating lines 4 are used when objects which only partially fill the diagrams vertically, such as checks, &c., are to be photographed. By applying the checks or other object to the upper portion of the particular diagram, the horizontal dimension of which corresponds to the horizontal dimension of the object, and in such a way that the object occupies a space between the top line of such diagram and one of these radiating lines, it will be seen by the operator that the measuring device is to feed so many inches of sensitized material as is indicated by the particular radiating line 4 with which the lower edge of the object registers. For example, if the object has a horizontal dimension equal to the horizontal dimension of the diagram 15, and is applied to the upper portion of this diagram so that the upper edge of the object coincides with the top line of this diagram, and if the lower edge of the object registers with the radiating line designated 5, it will then be indicated by the chart that a length of sensitized material five inches long will be re-

- quired for a reproduction of such object. The lens and copyholder will be adjusted in this instance as in the preceding instance where the object completely filled the diagram and, hence, the exposure takes in the full width of the sensitized material.
- Of course, it will be understood that the sensitized material is fed forward the amount indicated by the chart for each object after the exposure of such object has been made. It will also be understood that, in each instance, the reproduction will take in substantially the full width of the sensitized material, this being provided for by the different focuses indicated by the focusing card for the lens and copyholder, and that the radiating lines which subdivide the diagram vertically indicate the length of photographic material required for each object, thus economizing in the amount of sensitized material.

I claim as my invention:—

1. In photographic apparatus, an object support having a chart provided with diagrams for positioning an object, said diagrams being subdivided to indicate the amount of sensitized material required for the reproduction of an object.
2. In photographic apparatus, an object support provided with an object-positioning chart embodying a series of diagrams of graduated sizes, and means common to and subdividing said diagrams to indicate the amount of photographic material required for the reproduction of an object positioned with reference to the chart.
3. In photographic apparatus, an object support provided with a chart embodying a series of diagrams of graduated sizes having a common center and having means subdividing the diagrams vertically, and means for feeding sensitized material vertically before the chart in measured lengths as indicated by the subdivisions of said diagrams.
4. In photographic apparatus, an object-receiving chart embodying a series of diagrams of graduated sizes having a common center, and radially extending lines subdi-

viding the diagrams symmetrically in one direction, and indicating the amount of photographic material required for reproduction of an object.

5. In photographic apparatus, an object-receiving chart embodying a series of rectangular diagrams of graduated sizes having a common center and divided centrally into two horizontally spaced complementary sections, and radiating lines subdividing the diagram sections vertically and indicating the amount of photographic material required for reproduction of an object.

6. In photographic apparatus, the combination of an object-receiving chart embodying diagrams of graduated sizes and having individual index characters, and means subdividing the diagrams in one direction, a lens, the lens and chart being relatively adjustable for focusing, focusing scales for the lens and chart, means for indicating the different positions to be occupied by the lens and chart according to the diagrams of the chart, and means for feeding sensitized material in the optical field of the lens in amounts indicated by the subdividing means of the diagram.

7. In photographic apparatus, the combination of an object-receiving chart embodying diagrams of graduated sizes having a common center and having individual index characters, means subdividing the diagrams in one direction, a lens, and means for feeding sensitized material in the optical field of the lens in amounts indicated by the subdividing means of the diagrams, the lens and chart being adjustable relatively to one another and to said feeding means and having scales for determining the adjustments of the lens and chart according to the index characters of the diagrams on the chart.

In testimony whereof I have hereunto set my hand in presence of two subscribing witnesses.

WILLIAM R. SCHWAB.
